(57) CLAIM

The ornamental design for a shoe, as shown and described.

DESCRIPTION

FIG. 1 is a front perspective view of a shoe showing my shoe design;

FIG. 2 is a right side view of the shoe shown in FIG. 1;

FIG. 3 is a left side view of the shoe shown in FIG. 1;

FIG. 4 is a rear view of the shoe shown in FIG. 1;

FIG. 5 is a front view of the shoe shown in FIG. 1; and,

FIG. 6 is a front perspective view of a second embodiment of the shoe shown in FIG. 1.

The broken line showing of the heel, sole and beads is for illustrative purposes only and forms no part of the claimed design.
